UNITED STATES PATENT OFFICE.

MÁTYÁS MORÁNSKY, OF NEW YORK, N. Y.

SWIMMING DEVICE.

Application filed December 22, 1926. Serial No. 156,369.

The invention relates to a new and useful device in the nature of a swimming device, particularly adapted for use as an aid to swimming and which is attached to the feet 5 of the swimmer.

The object of the invention is to provide a swimming device of novel construction and arrangement of parts, hereinafter more fully described, claimed and illustrated in 10 the accompanying drawings, in which:

Fig. 1 shows my improved device attached to the feet of a swimmer, as same would appear when in use.

Fig. 2 is a front elevational view of my 15 improved device.

Fig. 3 is a top plan view thereof.

Fig. 4 is an enlarged transverse sectional view illustrating the method of attaching the movable members to the holding device, 20 as embodied in my improved swimming device.

Fig. 5 is a sectional view taken on the line 5—5 of Fig. 4.

Fig. 6 is a similar view taken on the line 25 6—6 of Fig. 4.

Fig. 7 is a fragmentary view, illustrating a modification of my improved device.

As here embodied my improved swimming 30 device comprises a bracket 10, of rectangular construction adapted to be slidably engaged over the instep of the foot of a swimmer. The flexible members 11 are attached to the bracket 10 and are extended therefrom and are provided with the usual buckle and engaging member, not shown in the accompanying drawings. The flexible members 11 are adapted to encircle the heel of the swimmer, as a means of holding the bracket 10 in place on the foot.

The extended member 12 is attached, as 35 at 13, by rivets, bolts or the like to the bracket 10 and is provided with enlarged oppositely extended bearing elements 14', of circular construction and which are provided with axial recesses adapted to receive

the enlarged extremities 15 of the brackets 16, which are of suitable size to pivotally engage therein. The said enlarged bearing elements 14 and 14', and the said enlarged extremities 15 are provided with co-axial 45 apertures adapted to receive the rivet 17, bolt or the like, as a means of pivotally attaching the brackets 16 to the extended member 12.

As shown in Fig. 3, the bearing element 50 14 and the bearing element 14' are provided

with slots 18 and 18' respectively, which communicate with the axial recess in the respective bearing elements for accommodating the brackets 16. The slot 18' of the bearing element 14' extends through a shorter arc than the slot 18 of the bearing element 14 and thus the ends of the slots which limit the movement of the bracket 16 retain the brackets at different angles of rotation relative to each other for a purpose 60 65 thereafter set forth.

The bracket 16 is provided with extended elements 19, to which the propelling member 20 is attached, as at 21, by rivets, bolts or the like. The propelling member 20 is of 70 semi-circular disc shaped construction and has attached thereto an edge member 23, preferably of rubber, of any suitable similar material of U shaped cross section and of suitable length to enclose or cover the 75 periphery of the propelling member 20, so as to prevent injury in event the propelling device when in motion should strike a person swimming.

The above described construction being 80 such as will permit the propelling members 20, it being obvious that both feet of the swimmer will have attached thereto my improved device, to assume an extended position when the foot of the swimmer is pushed through the water, as on the outward a propulsion stroke, so as to aid the swimmer. It being understood that the propelling members 20 will pivotally close on the return stroke, so as not to interfere or cause 85 delayed action to the said return stroke of the swimmer, it being clearly understood that the said propelling members will be relatively positioned at an angle, so as to effect more straight ahead propulsion, due 90 to the fact that the swimmer's feet, on the propulsion stroke are forced outwardly at an angle to the direction of the active propulsion direction, as is commonly the fact 95 when swimming.

Referring in particular to Fig. 7, the propelling members 20 may be pivotally attached to separate brackets 25, which are attached, as at 26, by rivets, bolts or the like 100 to the above mentioned bracket 10.

Having thus described my invention, what I claim as new and desire to protect by Letter Patent of the United States is as follows:

1. In a swimming device of the class de- 110

scribed, a bracket adapted to slidably engage over the foot of a swimmer, flexible members attached to and depending from the said bracket, as a means of attaching the 5 said bracket to the foot of the swimmer, oppositely positioned bearing elements mounted on said bracket having arcuate slots therein, the arcuate slot of one of said bearing members being extended through a 10 longer arc than the slot of the other bearing members, brackets disposed through said slots and pivotally mounted on said bearing members, and propelling members attached to said brackets, said propelling members 15 being retained in relative angular position to each other by engagement of said brackets with the end of said slots when said propelling members are in extended position.

2. In a swimming device of the class de- 20 scribed, a bracket adapted to slidably engage over the foot of a swimmer, flexible members attached to said bracket for attaching the same to the foot of a swimmer, a bearing member mounted on one side of said bracket, 25 a propelling member pivotally mounted on said bearing member adapted to be retained thereby substantially in the plane of said bracket when said propelling member is in extended position, a second bearing member 30 mounted on the other side of said bracket, and a second propelling member pivotally mounted on said second bearing member adapted to be retained thereby in angular relation to said first mentioned propelling

member when said propelling members are 35 in extended position.

3. In a swimming device of the class de- 40 scribed, a bracket adapted to be mounted on the sole of the foot of a swimmer, spaced bearing members mounted on said bracket 45 adjacent the sides of the foot of a swimmer, and propelling members pivotally mounted on said bearing members adapted to be re- tained by said bearing members in relative angular planes when in extended position.

4. In a swimming device of the class de- 50 scribed, a bracket adapted to be mounted on the sole of the foot of a swimmer, spaced bearing members mounted on said bracket 55 adjacent the sides of a foot of a swimmer, a propelling member pivotally mounted on one of said brackets adapted to be retained thereby in a plane parallel with the plane of the sole of said swimmer when said propelling member is in extended position, and a propelling member pivotally mounted on the other bearing member adapted to be re- 60 tained in a relative angular plane to the plane of the sole of the foot of the swimmer when said propelling member is in extended position, said propelling members being adapted to be rotated to parallel planes sub- 65 substantially perpendicular to the plane of the sole of the foot of a swimmer.

In testimony whereof I have affixed my 65 signature.

MÁTYÁS MORÁNSKY.
